Application April 29, 1936, Serial No. 76,993

9 Claims. (Cl. 200—24)

This invention relates to a timed control system.

The chief object of this invention is to provide a device which, in one form of the same, is of multiple character, whereby the various timed cycle operations of a signal system may be obtainable therefrom.

The full nature of the invention will be understood from the accompanying drawing and the following description and claims:

Fig. 1 is a top plan view of one embodiment of the invention showing the same of multiple form. Fig. 2 is a conventional wiring diagram of the system circuits. Fig. 3 is a transverse sectional view taken on the line 3—3 of Fig. 1 and in the direction of the arrows. Fig. 4 is a side elevation of one of the rotary switches.

In Fig. 1, 10 indicates a suitable container on the face of which is mounted three switches 11, 12 and 13. Within the container is suitably mounted a motor 14 which drives a speed reducer indicated generally by the numeral 15, driving in turn a three-step pulley structure 16 belt connected as at 17 to a complementary three-step pulley structure 18 carried by a shaft 19 rotatably supported in bearings 20 and 21 formed in the end frames 22 and 23 respectively. Rigid with the shaft 19 is a cone 24. Suitably secured in bearings 25 and 26 in the frames 23 and 22 respectively are cylindrical rods 27. These rods 27 lie below and to one side of the shaft 19 and the shaft is positioned therebetween. The container is provided with a cover structure which may be of detachable character and which is not herein shown completely. A portion 29 of said cover is, however, rigidly secured as at 28 to the container 10 and the same is trapezoidal in character, the inclination of the two inclined sides corresponding to the inclination of the elements of the cone.

The cover 29 has projecting therefrom along opposite sides and in spaced relation a plurality of pins 30 which project outwardly into elongated openings 31 in stationary portions 32 of the cover structure. An insulation base 33 is pivotally supported on rod 27 and is slidably supported thereon and extending upwardly therefrom for a handle member 34 adapted to seat in any one of the recesses formed between any two adjacent pins 30.

An arm 35 is suitably secured as at 36 to the base 33 and the arm carries a counter-balance 37 adjustably secured thereto by the headless set screw 38. The weight normally constrains the base structure toward the cone. The base structure is slotted as at 39. The base is of insulation material. A shaft 40 extends through the base

and at right angles to the opening 37 and projects outwardly from the base at opposite sides thereof as at 41 and 42. A spring member 43 bears on one end of the projecting shaft and is suitably secured to the insulation base as at 44. The stud 44 is locked to the base by a nut not shown and another nut on the same stud is adapted to secure a circuit wire thereto. Another stud 45 is similarly mounted in the base and is similarly adapted to secure another circuit wire. It also similarly secures a spring contact 46 to the base and said contact lies in a plane at right angles to the plane of contact portion 43. The other projecting end of shaft 40, indicated by the numeral 42, has rigidly secured to it at 47 a cam 48. Thus, when the shaft 40 is rotated, a circuit will be completed from spring contact 43 to spring contact 46 at predetermined intervals, depending upon the rotation of the shaft.

There is mounted upon shaft 40 a wheel 49 and the same is rubber tired as at 50 and this rubber tired wheel is adapted to frictionally engage the cone 24.

As the base structure is moved from the top to the bottom of Fig. 1, or from the small end 25 to the large end of the cone, the number of closures of the circuit per unit of time will increase in proportion to such shifting. Conversely, as the base is moved in the opposite direction, the number of circuit closures per unit of time will 30 be decreased. This is because the diameter of the rotating wheel, which is rubber tired, is fixed, whereas the diameter of the cone at any contacted section determines the peripheral distance and at constant cone speed the wheel will rotate 35 faster per unit of time when contacting the larger end of the cone than it will when contacting the small end of the cone.

It will also be observed, see Fig. 3, that the counter-balance 37 normally constrains the wheel 49 into cone contact and normally retains the handle member 34 into a selected recess. The pins 30 also prevent the friction wheel and its supporting structure from gradually creeping toward the slower end of the device, which is the smaller 45 end. In the container 10 shown in Fig. 1, the numerals 50 indicate two transformers, each of which has secondary terminals 61a, 61b and 61c.

Reference will now be had to the circuit shown in Fig. 2. In said figure, 70 indicates one power 50 main and 71 another. The line 72 from main 70 is associated with the switch 12 and the line 73 therefrom is connected to the motor 14, the line 74 therefrom being connected to line 71. Line 75 is connected to one terminal of one trans-

former 60 and another branch line 76 is connected to a corresponding terminal of another transformer 60, 77 indicating the primary windings thereof. The other terminal of the other transformer is connected by the line 79 to the switch 13. The opposite terminals of these switches are connected together by the line 80, in turn connected by line 81 to the return line 11. The secondary windings 82 of these transformers are shown provided with three taps which have terminals 61a, 61b and 61c. These taps provide a variation of secondary voltage. Since this transformer represents a 110 to 18 volt transformation, the voltage across 61a to 61b is 6 volts, from 61b across to 61c is 12 volts, while the voltage from 61a to 61c is 18 volts. A line 83 connects to the bolt 45 shown in Fig. 4 and thus is electrically connected to the spring contact 46. The cam 48 is in electrical connection by the spring contact 43 and the latter, through the bolt 44, see Fig. 4, is in electrical connection with line 84 which is herein shown as having a branch 85 and a branch 86 connected to one terminal of a bell 87 and one terminal of a lamp bulb 88, respectively. The other terminal of each of these units is connected by lines 89 and 90, respectively, to a line 91 which connects to the tap 61c, line 83 being connected to the tap 61a.

Thus, when the switch 13 is closed and switch 12 is closed, the cone is caused to revolve, which, if the tiltable switch structure is positioned as shown in Fig. 3, secures repetitious closing of the circuit through the cam 48 and the spring contact 46 for illuminating the lamp 88 and ringing the bell 87.

If a multiple device is desired, the other transformer is utilized and duplicate signals are provided, such an arrangement being controlled by the switch 11. It will be apparent that either of the switches 11 or 13 may be closed and thus either signal circuit conditioned for repetitious operation of the signals included therein. Opening the motor switch 12, unless one of the cams happens to register with its spring contact, will not result in the operation of the signal system.

In order to shift the device from one predetermined time cycle to another, the operator merely, while the motor is running and while the transformer control switch is closed, engages handle 34, tilts the base structure away from the cone until the handle clears the outer ends of the adjacent pins 39 and then the entire base structure and switch arrangement is shifted longitudinally into the selected new position and when released, the weight 37 moves the wheel 50 into cone contact and the handle 34 into the selected recess and retains the handle in the latter and maintains the wheel in cone contact.

While the invention has been described in great detail in the foregoing description and two forms thereof have been illustrated in the drawing, it is to be understood that such illustration and description is illustrative only and not restrictive in character. Various modifications of the invention which will readily suggest themselves to persons skilled in the art are considered within the broad scope of the invention as defined in the appended claims.

The invention claimed is:

1. An adjustable periodic switch device including a constant rotatable cone, a support the longitudinal axis of which is parallel to the surface of said cone, a base structure slidable longitudinally thereon, switch means carried by the base structure, and cone engaging wheel means

supported by the base structure adapted for rotation by the cone for cyclic operation of the switch means, said base structure also being tiltable on said support toward and away from the cone for moving the wheel means into and out of cone engagement for switch operation or non-operation during continuous cone rotation. 5

2. An adjustable periodic switch device including a constant rotatable cone, a support the longitudinal axis of which is parallel to the surface 10 of said cone, a base structure slidable longitudinally thereon, switch means carried by the base structure, cone engaging wheel means supported by the base structure adapted for rotation by the cone for cyclic operation of the switch 15 means, said base structure also being tiltable on said support toward and away from the cone for moving the wheel means into and out of cone engagement for switch operation or non-operation during continuous cone rotation, and means 20 for retaining the base structure on the support in the selected longitudinal adjustable position.

3. An adjustable periodic switch device including a constant rotatable cone, a support the longitudinal axis of which is parallel to the surface 25 of said cone, a base structure slidable longitudinally thereon, switch means carried by the base structure, and cone engaging wheel means supported by the base structure adapted for rotation by the cone for cyclic operation of the switch 30 means, said base structure also being tiltable on said support toward and away from the cone for moving the wheel means into and out of cone engagement for switch operation or non-operation during continuous cone rotation, the pivotal 35 axis of the base structure upon said support being located below the axis of cone rotation and at a horizontal distance therefrom greater than the sum of the radii of the cone and the wheel means of the respective circumferences of a section perpendicular to the cone axis and including the point of tangency therebetween, whereby the base structure when tilted beyond the vertical toward the cone is normally constrained into cone engagement by the weight of the structure and when 45 reversely tilted from the vertical is normally constrained and maintained in non-cone engaging position.

4. An adjustable periodic switch device including a constant rotatable cone, a support the longitudinal axis of which is parallel to the surface 50 of said cone, a base structure slidable longitudinally thereon, switch means carried by the base structure, cone engaging wheel means supported by the base structure adapted for rotation by the 55 cone for cyclic operation of the switch means, said base structure also being tiltable on said support toward and away from the cone for moving the wheel means into and out of cone engagement for switch operation or non-operation during continuous cone rotation, and adjustable means carried by the base structure for insuring predetermined structure contact between the cone and the wheel means.

5. A device as defined by claim 2, characterized 65 by the retaining means including a member having a pocketed edge substantially parallel to the support axis with the pocket openings substantially perpendicular thereto and by the addition of a handle extension upon said base structure and 70 projecting above said pocketed member, the handle extension being seatable in any one of the pockets and the upper end thereof being exposed for such selected positioning of the base.

6. A dual switch structure of periodic char- 75

acter, including a constant rotatable cone, a pair of supports each having a longitudinal axis parallel to the surface thereof, the cone being positioned therebetween, a base structure longitudinally slid able on each support, switch means carried by each base structure, and cone engaging wheel means on each base structure rotatable by the cone and arranged for cyclic operation of its switch means carried by its base structure.

7. A dual switch structure of periodic character, including a constant rotatable cone, a pair of supports each having a longitudinal axis parallel to the surface thereof, the cone being positioned therebetween, a base structure longitudinally slid able on each support, switch means carried by each base structure, and cone engaging wheel means on each base structure rotatable by the cone and arranged for cyclic operation of its switch means carried by its base structure, each base structure being tilt able on its support for moving its wheel means into and out of cone engagement for operation or non-operation of its switch means in cone rotation.

8. A dual switch structure of periodic character, including a constant rotatable cone, a pair of supports each having a longitudinal axis parallel to the surface thereof, the cone being positioned therebetween, a base structure longitudinally slid able on each support, switch means carried by each base structure, and cone engaging wheel means on each base structure rotatable by the cone and arranged for cyclic operation of its switch means carried by its base structure, each base structure being tilt able on its support for moving its wheel means into and out of cone engagement for operation or non-operation of its switch means in cone rotation, the pivotal axis of each base structure being located below the axis of cone rotation and at a horizontal distance

therefrom such that when the wheel means carried by the base structure is in cone engagement the base structure is tilted beyond the perpendicular through its pivotal support and toward the cone, said last mentioned base structure being tilt able beyond the perpendicular in the opposite direction to insure non-engagement of the wheel means thereof with the cone. 5

9. A dual switch structure of periodic character, including a constant rotatable cone, a pair of supports each having a longitudinal axis parallel to the surface thereof, the cone being positioned therebetween, a base structure longitudinally slid able on each support, switch means carried by each base structure and cone engaging wheel means on each base structure rotatable by the cone and arranged for cyclic operation of its switch means carried by its base structure, each base structure being tilt able on its support for moving its wheel means into and out of cone engagement for operation or non-operation of its switch means in cone rotation, the pivotal axis of each base structure being located below the axis of cone rotation and at a horizontal distance therefrom such that when the wheel means carried by the base structure is in cone engagement the base structure is tilted beyond the perpendicular through its pivotal support and toward the cone, said last mentioned base structure being tilt able beyond the perpendicular in the opposite direction to insure non-engagement of the wheel means thereof with the cone, and adjustable means associated with each base structure in addition to its constraint for securing predetermined pressure contact between the wheel means supported by said last mentioned base structure and the cone. 10 15 20 25 30 35
